UNITED STATES PATENT OFFICE.

JOSEPH FREUND, OF ST. LOUIS, MISSOURI, ASSIGNOR TO AMERICAN CEMENT TILE MANUFACTURING COMPANY, OF WAMPUM, PENNSYLVANIA, A CORPORATION OF PENNSYLVANIA.

TILE ROOF AND TILE THEREFOR.

1,082,076.

Specification of Letters Patent.

Patented Dec. 23, 1913.

Application filed June 12, 1912. Serial No. 703,915.

To all whom it may concern:

Be it known that I, JOSEPH FREUND, a resident of St. Louis, Missouri, have invented a new and useful Improvement in 5 Tile Roofs and Tiles Therefor, of which the following is a full, clear, and exact description, reference being had to the accompanying drawings, forming part of this specification, in which—

10 Figure 1 is a plan view of a portion of a roof; Fig. 2 is a section on the line II—II of Fig. 1; Fig. 3 is a similar view on the line III—III of Fig. 2; Fig. 4 is a detail plan view of a portion of two tiles and a 15 portion of one of the rolls partially in section; Fig. 5 is a detail sectional view on the line V—V of Fig. 2; Fig. 6 is a detail sectional view similar to Fig. 3, on the larger scale; and Fig. 7 is a perspective 20 view of one of the rolls.

My invention relates to an improvement in tile roofs and tiles therefor, and is designed to provide a roof of this character, in which the tiles are made to prevent the 25 snow and rain from being driven into the building at the joints between the adjacent tiles.

Another object of my invention is to provide a roll for covering the joint between 30 adjacent tiles, which can readily be secured to the purlins to prevent the roll and the underlying tiles from being blown from the roof.

Still another object of my invention is to 35 provide a roll which is so shaped and reinforced that it can readily be shipped without breaking.

I am aware that rolls have been used to 40 cover the joints between adjacent tiles, but do not know of any roll which would be satisfactory when used with cement tiles which are now in common use and which measure approximately twenty-six inches by fifty-two inches.

45 The precise nature of my invention will be best understood by reference to the accompanying drawings, which will now be described, it being promised, however, that various changes may be made in the details of construction and general arrangement of the parts, without departing from the spirit and scope of my invention as defined by the appended claims.

In the drawings, the numeral 2 designates 55 the tiles, which are provided with down-

wardly extended projections 3 on the bottom and at the upper ends thereof, and which are arranged to engage purlins 4 for supporting the roof. Each of these tiles is provided with a longitudinal rib 5, along 60 each of its longitudinal edges, and a flange 6 adjacent to each of said ribs.

7 designates a recessed bead in each of the tiles, the beads in the tiles in one course being arranged to overlap the rolls covering the joints between tiles in an adjacent course, as hereinafter described. The lower corners of each of the tiles are cut away, as indicated at 8, and the upper portions of each of the ribs 5 are cut away, as indicated 70 at 9.

10 designates the rolls, each of which is provided with a downwardly extending reinforced web 11; and 12, 12 designate recesses in the under face of said roll, one on 75 each side of the web 11. The upper ends of these recesses are closed by the short end projections 13, and the lower ends thereof are closed by the projections 14, which are approximately the same depth as 80 the reinforcing web 11.

15 designates a reinforcing member, which may be formed of wire gauze, expanded metal, or any suitable material, and which is bent upon itself in the lower portion of the web 11 and extends upwardly 85 therein and then downwardly on each side around the recesses 12.

16 designates a reinforcing rod extending through the web 11, which acts as a tension 90 member for the web 11, and 17 are loops extending downwardly from the rib 11, the inner ends thereof being secured within the body of the roll during the formation thereof. The lower outer edges of the roll 95 10 are recessed as indicated at 18, and these recesses are adapted to be filled with cement to prevent moisture from being driven in between the roll and the tile.

The roof is laid in the following manner:—The tiles 2 are laid in the course A indicated in Fig. 1, so that their projections 3 engage the second purlin. After the proper number of tiles have been laid along the first course, rolls 10 are then placed over 100 the junctions between adjacent tiles in the first course, the ribs 5 of the tiles entering the recesses 12 in the rolls, and the closures 13 resting in the cut-away portions 9 of the ribs 5. As can be seen by reference to Fig. 110

5, the projections 14 enter the cut-away portions 8 in adjacent tiles so as to prevent moisture being driven in at the lower ends of the tiles at the junction between them. 5
 5 After the rolls in the first course have been placed in position, they are secured in place by means of wire or any suitable securing member 10, which is secured to the lower purlin and to the loops 17 to retain the 10 lower ends of the rolls in the first course, together with the lower ends of the tiles below them in position on the roof. The second and third courses are then laid in a similar manner. The last course is also 15 laid in a manner similar to the first course, but the upper ends of the rolls 10 are secured by means of wires 20 which engage the upper purlins and loops 17 in the upper ends of the rolls in the top course. After 20 the roof has been completed, the grooves 18 in the edges of the rolls 10 are filled with cement, as indicated at 21 in Fig. 6.

By reference to Fig. 6, it will be readily seen that the flanges 6 are slightly above 25 the upper portions of the tiles which will prevent the water from being driven in between the bottoms of the rolls and the tile, and even though water should be driven in between the tiles and the rolls the ribs 5 30 will prevent the water from being driven into the building.

The advantages of my invention result from the provision of a tile in which both 35 its longitudinal edges are the same. Further, from the provision of a roll having a reinforcing rib which is arranged to extend down between adjacent tiles. Further, from the provision of means for securing 40 the rolls and the underlying tiles to the roof frame structure.

I claim:—

1. A tile roof having a plurality of courses of tiles and a plurality of rolls for each course, there being one roll for each 45 joint between adjacent tiles in the same course, each of said rolls having two longitudinal recesses in its lower face and a downwardly extending longitudinal rib between said recesses, the adjacent longitudinal edges of each tile at said joint having an upwardly extending longitudinal rib seated in the recesses in their respective roll, the lower faces of the last mentioned projections closing the lower end of the recesses, the lower faces of the last mentioned projections being flush with the bottoms of the tiles in the same course to seal the ends of the joints between 50 the tiles; substantially as described.

2. A tile roof having a plurality of courses of tiles, and a plurality of rolls in each course, there being one roll for each joint between adjacent tiles in each course, each of said rolls having two longitudinal recesses in its lower face and a downwardly extending longitudinal rib between said recesses, the adjacent longitudinal edges of each tile at said joint having an upwardly extending longitudinal rib seated in the recesses in their respective roll, the lower corners of each tile being cut away at the joint between adjacent tiles, and a downwardly extending transverse projection on the lower end of each roll seated in the cut-away portions in the adjacent tiles, the last projections closing the ends of the recesses of the rolls and the ends of the joints between adjacent tiles; substantially as described. 75

3. A tile roof having a plurality of courses of tiles, and a plurality of rolls in each course, there being one roll for each joint between adjacent tiles in each course, each of said rolls having two longitudinal recesses in its lower face and a downwardly extending longitudinal rib between said recesses, the adjacent longitudinal edges of each tile at said joint having an upwardly extending longitudinal rib seated in the recesses in their respective roll, the lower corners of each tile being cut away through the joint between adjacent tiles, and a downwardly extending transverse projection on the lower end of each roll seated in the cut-away portions in adjacent tiles, the last 85 mentioned projections closing the ends of the recesses of the rolls and the ends of the joints between adjacent tiles, and a transverse projection on the other end of each of said rolls, the last mentioned projection engaging the ends of the ribs on adjacent tiles, the transverse projections on the rolls being arranged to prevent longitudinal movement between the rolls and tiles; substantially as 90 described. 95

4. A roll for tile roofs having two longitudinally extending recesses in its lower face, a longitudinally extending reinforcing rib between said recesses, a closure for the upper ends of said recesses extending to 100 the lower edge of the roll, and a closure for the lower ends of said recesses extending to a point below the lower edge of the roll; substantially as described. 105

In testimony whereof, I have hereunto set 110 my hand.

JOSEPH FREUND.
